O. G. VANDERHOOF.
MACHINE FOR PRINTING PAPER BAGS.

No. 424,150.

Patented Mar. 25, 1890..

UNITED STATES PATENT OFFICE.

ORSON G. VANDERHOOF, OF LEXINGTON, KENTUCKY.

MACHINE FOR PRINTING PAPER BAGS.

SPECIFICATION forming part of Letters Patent No. 424,150, dated March 25, 1890.

Application filed February 28, 1889. Serial No. 301,534. (No model.)

To all whom it may concern:

Be it known that I, ORSON G. VANDERHOOF, a citizen of the United States, residing at Lexington, in the county of Fayette and State 5 of Kentucky, have invented certain new and useful Improvements in Machines for Printing Paper Bags and Wrappers; and I do hereby declare the following to be a full, clear, and exact description of the invention, such 10 as will enable others skilled in the art to which it appertains to make and use the same.

This invention relates to rotary printing-machines; and it consists in certain improvements in the construction of the same, as 15 hereinafter described and claimed. In the construction as herein described the machine is adapted for printing advertisements on paper bags and wrappers, and is provided with certain devices for holding the bags and 20 wrapper-sheets in place while being printed.

In the accompanying drawings, Figure 1 represents a plan view of a printing-machine provided with my improvements. Fig. 2 is a side view of the same, parts being removed. 25 Fig. 3 is an end view showing the rear end of the machine. Fig. 4 partly illustrates the spring-arms of the bag-holding devices.

A designates the base of the casing, to which the standards B are secured, the opposite 30 standards being connected by the cross-pieces a.

C indicates a board which rests on the base A, or on tracks secured thereto, and forms a base for the operating devices. To the board 35 C are fastened the opposite standards D, which are connected at the top by a cross-piece b. To the board C are also secured the curved slotted standards E and E', two standards E being located opposite each other toward the forward end of the board, and two standards E' being in opposite positions toward the rear end, for the purpose herein- 40 after mentioned.

F and F' indicate spring-arms, which are 45 usually constructed of wire and are connected with the board C, the two arms F extending forward and the arms F' extending rearward, as shown. The inner ends of these spring-arms are connected by the wire which 50 crosses the board C and is formed into a spring F², the wire being secured by staples

to the board, which is recessed to receive the spring.

G indicates a roller, which is carried by the forward arms F. The journals of said roller 55 may be loosely held by said arms, or the latter may be bent inward at their forward extremities and passed through the slots in standards E and into holes in the roller. G' indicates another roller, which is carried by 60 the two arms F' in like manner as roller G is carried by the arms F. These two rollers extend over and across the board C, and the spring F² and arms are so constructed that they tend to press the rollers down to the 65 board C. To assist somewhat in such downward pressure of the rollers, springs c are placed in the slots of the curved standards E E', over the journals of the rollers, which may be extended into said slots, or over the 70 spring-arms when the latter are bent, and passed through the slots into the rollers. The front roller G is provided with a covering of absorbent material to take up moisture from the impressions of the printing-roller. 75 The roller G' is usually provided with a covering of rubber or other similar material.

The printing-roller H is journaled in a frame which consists of the sides J with transverse connections. The said sides are provided at their forward ends with curved slots d, through which the turned ends of the arms F are passed. The rearward ends of the sides are made to hook on a rod or wire e, which crosses the frame. The sides J are slotted at 85 f to receive journal-boxes of the printing-roller and the springs g placed above said boxes to allow the roller a slightly-yielding movement in case of unevenness from any cause in the pile of bags or sheets under the 90 roller. The springs h are connected with the forward ends of the sides J and with the board C and assist in bringing down the roller-frame as the pile of bags becomes reduced in size. 95

The printing-types are arranged on one side of roller H, so that they occupy not more than one-half of the peripheral surface, the remainder of such surface being left blank. The printing-roller is provided with raised 100 surfaces at its extremities, such surfaces being usually formed of rubber bands L. These

bands serve as bearing-surfaces for the roller on the bags when the latter are not in contact with the type, the projection of said raised surfaces being equal to that of the type.

5 An indicator *m* is placed on the shaft of the printing-roller to indicate the correct position of the roller for starting, the half part of the roller which carries the form of type being toward the rear when the indicating-hand points directly upward.

Adjacent to the printing-roller is a box *I*, which is journaled in the sides *J* and extends from one side to the other. The said box is divided into a number of compartments *k* for ink of different colors, and each compartment is open at the bottom and is provided with sponge, which rests upon an inking-roller *L'*, so that ink permeating the sponge may pass to the inking-roller. The sponge-box is held 15 to the roller by springs *n*. The side of the box *I* toward the roller *H* is extended at *o* to nearly touch the roller *L*, and is so constructed that the sponge cannot be displaced by the movement of the roller, and the ink is prevented from passing in too large a quantity 20 to the surface of the roller. The roller *L'* is journaled in slots in the sides *J* in position to ink the form on the printing-roller *H*. Tension-springs *p* are connected with the journals of roller *L'* and with the sides *J*.

At the rear end of the board *C* is a wire *q*, having both ends fastened to the board and curving over and across the same, said wire being braced by another wire *r*, which extends from a cross-bar carried by the standards *D*. A fine wire *s* is secured at one end to the curved wire *q*, and is passed down through the bags at the mouth ends, when said bags are placed on the board *C*, and is secured to said board at its rear end. This wire *s* is for the purpose of retaining the paper sacks or sheets in place during operation. As each sack is drawn forward after receiving an impression from the printing-roller, the wire *s* serves to hold the remaining sacks in place.

50 *M* indicates a blade which is used in detaching sheets of the required size when wrapping-sheets are being printed, the said blade being made fast to the ends of the arms *t*, which are loosely coupled to the extremities of spring-arms *E*, which are passed through eyes in arms *t*.

Apertures *v* are made in the standards *E* 55 *E'* for the insertion of pins under the spring-arms *F* *F'* when the latter are raised for the purpose of placing the bags or sheets to be printed on the boards *C*. Buttons (indicated at *u*) pivoted to the board *C* may also be used 60 to hold up the spring-arms while the sacks are being placed. The rollers *G* *G'* being raised, the bags to be printed are placed on the board *C*, as seen in Fig. 1, and the spring-arms are released and the rollers are brought 65 down by the springs to press against the bags. The printing-roller is adjusted in position

with the indicator *m* pointing directly upward, that part of the peripheral surface of the roller which bears the form being rearward. The first bag is then drawn forward 70 and the printing-roller and the other rollers in contact with the bag are rotated by the movement. When the printing-roller has made one-half of a revolution, the bag has received an impression from the form, and 75 when the bag has been entirely withdrawn the form has reached the surface of the next bag to be printed. As the bags are successively printed and drawn out, the pile diminishing in size, the rollers *G* *G'* are kept in 80 contact with the bags by the spring-arms, the printing-roller being also brought down by said arms and springs *h* and kept in contact with the bags remaining in the apparatus. The slots *d* in the sides *J* of the roller-frame 85 make allowance for any difference of movement between arms *F* and sides *J* during the downward movement.

When the bags have all been printed and drawn out and it is desired to print a new 90 lot, the board *C* may be withdrawn from the frame, and the frame which carries the printing devices may be unhooked and taken off, and a new lot of bags may then be placed on the board *C*, which is then returned to its 95 place in the frame, and is retained in place by one or more lugs *x*, which enter recesses *z*.

When paper for wrapping-sheets is printed, sheets of the required size may be detached by pulling the paper upward against the edge 100 of the blade *M*. The paper from which the sheet is detached by pulling upward against the edge of blade *M* is flat, cut into sheets, and provided with holes for the fine wire to pass through. As each sheet is pulled off, 105 the wire cuts its way through.

The apparatus may be inclosed by casing formed of plates of glass or other suitable material secured to the main frame, a swinging door being provided in front, as indicated 110 at *P*.

I claim—

1. In a printing-machine, the combination, with a printing-roller and a frame in which said roller is journaled, of a series of spring-arms provided with rollers at their free ends, and a base-board to which the inner ends of said arms are secured, two of said arms supporting the forward end of the frame in which the printing-roller is mounted, substantially 115 as and for the purposes described.

2. The combination, with a base-board, of the arms *F* and *F'*, secured to said board and provided with a spring *F²*, and rollers *G* and *G'*, which are carried by said arms, substantially 120 as and for the purposes described.

3. The combination, with a base-board provided with standards *D*, of the spring-arms *F* *F'*, rollers *G* *G'*, carried by said spring-arms, a frame which is provided with slots *d* and is 125 pivotally connected at its rear end with standards *D*, and connected at its front end with 130

the journals of rollers G, and a printing-roller and inking devices journaled in said frame, substantially as and for the purposes described.

5 4. The combination, with a base-board, of the spring-arms and two rollers carried by said arms, and a blade M, provided with arms t, which are pivotally connected with the journals of rollers G, substantially as set forth and described.

10 5. The combination, with a base-board provided with standards D and curved slotted standards E E', of the spring-arms, rollers G G', and springs e, in position to press down-

ward against the journals of said rollers, substantially as set forth. 15

6. The base-board provided with standards D, in combination with the spring-arms and rollers carried by said arms, the wires r and g, and vertical wire s, substantially as set forth. 20

In testimony whereof I have affixed my signature in presence of two witnesses.
